Primary Examiner — Ian Simmons*Assistant Examiner* — Dana L Meyrow(74) *Attorney, Agent, or Firm* — The Belles Group, P.C.(57) **CLAIM**

The ornamental design for a bottle, as shown and described.

DESCRIPTION

FIG. 1 is a top perspective view of a bottle showing my new design;

FIG. 2 is a front elevation view thereof, the right side, left side and rear elevation views being identical;

FIG. 3 is a front and side elevation view thereof;

FIG. 4 is a top plan view thereof, the opposing side details seen through the transparent surface not being shown for ease of illustration; and,

FIG. 5 is a bottom plan view thereof, the opposing side details seen through the transparent surface not being shown for ease of illustration.

The broken lines in the drawings illustrate the portions of the design that form no part of the claim.
